ABSTRACT OF THE DISCLOSURE

A heat pump system has two heat motor operated expansion valves connected in series between the two coils of the system. On the reversing valve side of the system a thermistor is connected between each coil and the compressor and each thermistor controls the heat motor of one of the valves. In one state of heat pump operation one expansion valve is driven full open while the other maintains control and the expansion valve operation is reversed in the other state of heat pump operation.

BACKGROUND OF INVENTION

Field of invention

This invention relates to heat pump systems and, more particularly, to control arrangements for such systems.

Description of prior art

Various heat pump systems have been proposed in the past. Generally these prior systems have been complex in their valving and also in their sensing and control arrangements. One class of such systems has used two expansion valves but, due to their mode of operation and/or design, have generally also required a check valve arrangement which complicated the overall system. Pat. 3,464,227 of Alan A. Matthies assigned to the assignee of this application, discloses and claims a specific expansion valve construction which permits control over heat pump operation with a single valve and eliminates the need for any check valves.

SUMMARY OF INVENTION

This invention has gone beyond such prior art practices and is a further, marked extension of the aforementioned system arrangements.

An object of this invention is to provide, a versatile, effective and positive control arrangement for a heat pump system and yet one which maintains a basically simplified arrangement. For the achievement of these and other objects, this invention proposes a heat pump system wherein a pair of valves are arranged between the system coils to control flow from one coil to the other. The valves are controlled by an operator which responds to an electrical input to vary valve position and flow in the system. The circuit elements are connected in the system so that in either state of heat pump operation one is positioned in the gas discharge of the compressor and the other in the suction line of the compressor and both respond to system conditions in those areas.

With this arrangement, in each operative state of the reversing valve one of the expansion valves is driven full open and is not called upon to meter the flow of refrigerant, while the other expansion valve continues to meter flow on the basis of the system condition at its circuit element. This eliminates the need for check valves, etc., and also provides an effective, simple and yet versatile control arrangement.

DESCRIPTION OF PREFERRED EMBODIMENT

The heat pump system in the drawing is illustrated with indoor coil 10, outdoor coil 12, two thermal electric expansion valves 14 and 16 in series between the coils at a common end of each coil, and the opposite ends of the coils are connected to compressor 18 through reversing valve 20. The reversing valve is of conventional construction and forms no part of this invention, hence it has not been illustrated and will not be described in detail.

Valves 14 and 16 are illustrated schematically in the form of an electrically energized heat motor operated valve. Each valve includes a valve member 22 and 24, connected in a conventional manner to a bimetal 26 and 28, the bimetals in turn being in heat transfer relation with heaters 30 and 32. The operative state of each bimetal is determined by the heaters and the valve members move with the bimetals relative to orifices 34 and 36 to control flow between the inlet and outlet of each valve and, correspondingly, in the system. The heaters are energized from source 38 and a switch 40 may be included in the heater circuit for selective control.

Heaters 30 and 32 are each connected in series with a thermistor 42 and 44. The thermistors control the input 25 to the heaters on the basis of a sensed condition in the system. The thermistors are suspended in the system conduit where they are subjected to self-generated heat, in the presence of refrigerant in a gaseous state the self-generated heat and hence temperature of the thermistors 30 is relatively high. The thermistors have a negative coefficient of resistance and, with an increase in temperature, their resistance is reduced producing a correspondingly high current in the heater which drives the heater open. Liquid refrigerant in the system, indicating an 35 excess of refrigerant being supplied, will contact and rapidly cool the thermistor increasing its resistance and reducing current in the heater. This modulates the valve closed, reducing the amount of refrigerant flow.

The construction and arrangement of the thermistor in 40 the system and its operation with respect to an expansion valve are more completely set forth in the copending application of Alan A. Matthies, Ser. No. 659,962, filed Aug. 11, 1967, entitled "Thermistor Controlled Refrigeration Expansion Valve" now Pat. 3,478,534 and assigned 45 to the assignee of this application. Reference is made to that application for a more complete description of the construction, arrangement, and operation of the thermistor should one become necessary.

Assuming a cooling cycle, coil 12 becomes a condenser 50 and coil 10 an evaporator. Thermistor 42 is now connected in the discharge gas from compressor 18 and its temperature rises decreasing its resistance and increasing current in heater 30 to drive the valve 14 full open. Valve 14 is in the liquid line and is opened full to freely pass 55 refrigerant. Thermistor 44 is in the suction line and will control its valve 16 in accordance with the state of the refrigerant to maintain 0° F. superheat if desired.

Should a heating cycle be selected the operation of the thermistors and their respective valves are reversed when 60 the reversing valve is operated. More particularly, thermistor 44 is now in the discharge gas of the compressor and causes its valve 16 to be driven full open while thermistor 42 is now in the suction line and maintains 0° F. superheat.

65 This arrangement provides accurate control over the heat pump operation and does not require additional system components such as check valves or the like.

Although but one embodiment of the present invention 70 has been illustrated and described, it will be apparent to those skilled in the art that various changes and modifications may be made therein without departing from

3

the spirit of the invention or from the scope of the appended claims.

I claim:

1. A heat pump system comprising, in combination, a compressor, 5 first and second coils, reversing valve means disposed between said compressor and one end of each of said coils for controlling the direction of flow through said coils from the discharge side of said compressor to the intake side 10 of said compressor, said reversing valve means having a first operative state directing flow through said coils in one direction and a second operative state directing flow through said coils in an opposite direction, 15 first and second flow control valve means connected, relative to flow between said coils, in series relation between the other ends of said coils for controlling flow between said coils, operator means connected to each of said valve means 20 and in response to an electric signal, operating said valve means to determine flow therethrough, a control circuit for said operator means including electrical circuit means characterized by having electric circuit characteristics which vary in accordance with 25 variations in refrigerant condition and control said operator means in accordance with said electric circuit characteristics, said electric circuit means connected in and exposed to the condition of said system 30 on the compressor side of both of said coils so that the condition of the refrigerant system in the area of said electric circuit means and the operative states of said valve means are varied in accordance with the sensed conditions of said system in the areas of 35 said electric circuit means, and said electric circuit means further characterized in that in said first operative state of said reversing valve means one of said operator means is caused to drive its valve means open and the other operator 40 means and its valve means control refrigerant flow and in said second operative state of said reversing valve means said other operator means is caused to drive its valve means open and said one operator 45 means and its valve means control refrigerant flow so that flow between said other coil ends occurs through both said first and second flow control valve means in both directions of flow through said coils. 50
2. The combination of claim 1 wherein 55 said operator means comprise heat motor means connected to each of said valve means and operative, in response to an electrical input, to vary the opening of and flow through said valve means, and wherein said electric circuit means is connected to said heat motor means for controlling the electrical input to said heat motor means in response to system condition. 60
3. The combination of any one of claims 1 and 2 wherein 65 said electric circuit means comprise thermistor means

4

operative to affect said control on the basis of the temperature of said thermistor means.

4. The combination of claim 2

wherein said heat motor means each include a thermal responsive element determining the position of said valve means and an electrically operated heater in heat transfer relation with said thermal responsive element to influence the temperature of said thermal responsive element, and wherein said electric circuit means comprise thermistor means connected to and controlling the operative state of said heaters.

5. The combination of claim 4 wherein said thermistors have negative temperature coefficients.

6. A heat pump system comprising, in combination, a compressor, first and second coils, reversing valve means disposed between said compressor and one end of each of said coils for controlling the direction of flow through said coils from the discharge side of said compressor to the intake side of said compressor, said reversing valve means having a first operative state directing flow through said coils in one direction and a second operative state directing flow through said coils in an opposite direction, first and second flow control valve means connected, relative to flow between said coils, in series relation between the other ends of said coils for controlling flow between said coils, operator means connected to each of said valve means for operating said valve means, control means connected to said operator means and exposed to said refrigeration system, said control means operative to sense a condition of said refrigeration system and operative to control said valve means on the basis of said sensed condition, and said control means further operative when said reversing valve means is in said first operative state to actuate one of said operator means to drive its valve means open and the other operator means and its valve means control refrigerant flow and when said reversing valve means is in said second operative state to actuate said other operator means to drive its valve means open and said one operator means and its valve means control refrigerant flow so that flow between said other coil ends occurs through both said first and second flow control valve means in both directions of flow through said coils.
